(57) CLAIM

The ornamental design for an air cleaner case cover for motorcycle, as shown and described.

DESCRIPTION

FIG. 1 is a perspective view of the front, top and left side of an air cleaner case cover for motorcycle showing our new design;

FIG. 2 is a perspective view of the front, top and right side
thereof;

FIG. 3 is a perspective view of the rear, bottom and left side
thereof;

FIG. 4 is a perspective view of the rear bottom and right side
thereof;

FIG. 5 is a front view thereof;

FIG. 6 is a rear view thereof;

FIG. 7 is a top view thereof;

FIG. 8 is a bottom view thereof;

FIG. 9 is a right side view thereof;

FIG. 10 is a left side view thereof; and,

FIG. 11 is a front view of the air cleaner case cover on a reduced scale, shown in position of use on a motorcycle which is shown in broken lines for illustrative purposes only and forms no part of the claimed design.
